COVER ATTACHMENT FOR TELEPHONE HANDSETS

Walter Eric Youngberg, Cranston, R.I., assignor to
Gorham Corporation, Providence, R.I.

Filed Aug. 10, 1966, Ser. No. 3,416

Term of patent 14 years

(Cl. D26—14)

FIG. 1 is a side elevation of a cover attachment for telephone handsets showing my new design.

FIG. 2 is an end view thereof.

FIG. 3 is a top plan view thereof, the right-hand portion of the decorative motif fragmentarily shown, is a mirror image of the left-hand portion shown,

FIG. 4 is a sectional view taken on line 4—4 of FIGURE 3, and

FIG. 5 is a fragmentary view as seen from the opposite end of FIG. 2 showing the central hole for the cord.

The decorative motif is omitted from FIGS. 1 and 2 for ease of illustration.

The broken lines representing the telephone handset is shown for illustrative purposes only.

I claim:

The ornamental design for a cover attachment for telephone handsets, as shown and described.
